UNITED STATES PATENT OFFICE.

SAMUEL A. JACOBS, OF BROOKLYN, NEW YORK, ASSIGNOR TO MERGENTHALER LINOTYPE COMPANY, A CORPORATION OF NEW YORK.

DESIGN FOR A FONT OF SYRIAC TYPE.

55,049.

Specification for Design.

Patented May 4, 1920.

Application filed December 11, 1919. Serial No. 344,153. Term of patent 14 years.

To all whom it may concern:

Be it known that I, SAMUEL A. JACOBS, a subject of the Shah of Persia, residing at Brooklyn, county of Kings, and State of New York, have invented a new, original, and ornamental Design for a Font of Syriac Type, of which the following is a specification, reference being had to the accompanying drawing, forming part thereof.

The drawing is a representation of a font of Syriac type illustrating my new design.

I claim:

The ornamental design for a font of Syriac type as shown.

SAMUEL A. JACOBS.

Witnesses:

L. E. MORRISON,
W. J. DOLAN.
